1,927,704

MULTIPLEX DROP CHANNEL SYSTEM

Frederick G. Halliden, Bellerose, N. Y., assignor to International Communications Laboratories, Inc., Newark, N. J., a corporation of New York

Application November 9, 1931. Serial No. 573,930

9 Claims. (Cl. 178—53)

The present invention relates to printing telegraph systems and especially to synchronous multiplex systems. More particularly the invention pertains to drop channel repeaters, which are well known in the art.

5 Drop channel repeaters are used to provide channels of communication between terminal stations and intermediate stations. For example, a drop channel repeater might be installed at an intermediate point on a two-channel multiplex 10 system and would provide in place of two communication channels between the terminal stations a single channel between terminals and an additional channel between each terminal and the intermediate station. Of course, such repeaters may be installed in systems of more than 15 two channels. In the common multiplex system, using drop channel repeaters, synchronism is maintained by correcting the distributor at the drop channel or intermediate station to the speed 20 of the transmitting distributor at a terminal, and, in turn, correcting the receiving distributor at the other terminal to the drop channel distributor. The maintenance of synchronism, or 25 correction, is achieved by altering the phase displacement between the sending and receiving distributors by increasing or decreasing the speed of the receiving distributor under control of impulses generated from the line signals. Correcting means, as applied to drop channel distributors, are well explained in Connery Patents Nos. 1,599,514 and 1,679,852.

It is obvious that in a system, as above set forth, failure of a line section between adjacent 35 stations causes a loss of synchronism, and causes all channels of the system to be inoperative. Synchronism may be restored by adjusting the drop channel distributor to operate at a speed which is the mean of the transmitting 40 distributor speed and the receiving distributor speed. However, when this is done manually a considerable period elapses before traffic can be resumed over the re-established channel. In accordance with this invention switching means 45 are provided to maintain synchronism on one section of a line including a drop channel repeater when another section has failed.

It is an object of the invention to maintain 50 synchronism between multiplex distributors over one section of a line when an adjacent line section has failed. To accomplish this object, and in accordance with the features of the invention, means is provided at the intermediate station 55 which co-operates with the correcting system and responds to the failure or interruption of

one section of the line to operate the distributor of the drop channel or intermediate station at a mean value of speed. This will permit maintenance of synchronism over the good line section.

Referring to the drawing:

Figure 1 illustrates two terminal stations 1 and 3 connected through the intermediate drop channel station 2. The broken lines show some of the various traffic channels and the direction thereof possible in such a system. These lines are sufficient to illustrate one adaptation of the invention; and

Figure 2 shows a detailed arrangement of the invention as used at the intermediate station 2. It is to be noted that this invention is useful 70 with any of the well-known types of multiplex systems utilizing distributors either of the cam type, as disclosed in Connery 1,599,514, or the rotary type which is also in common use.

Referring now to Figure 1, there is shown a 75 two-channel multiplex system comprising terminal stations 1 and 3 connected to a drop channel station 2 by means of line sections 4 and 5. Such a system provides for a channel of communication between stations 1 and 3, and 80 for channels of communication also through the drop channel repeater from station 1 to station 2 and from station 2 to station 3. Normally, all channels are duplexed so that six messages may be transmitted simultaneously.

While this drawing illustrates a two-channel system with a single drop channel repeater, it is to be noted that the invention, hereinafter described in detail, may be used with other multiple channel systems and may be utilized when 90 more than one intermediate station is provided for operation with the terminals.

Referring now to Figure 2, there are shown the elements necessary for practicing the present invention in such detail only as is necessary for a 95 complete understanding thereof. Relay 15 controls tongue 6 so that positive or negative battery is applied to conductor 7 which, in turn, leads to the rotary distributor. Line signals are utilized to provide corrector action in the well-known manner, as shown, for example, in Connery Patents 1,599,514 and 1,679,852. Signals coming in over line 16 cause operation of relay 15 and apply positive or negative battery over tongue 6 of relay 15 and conductor 7 to the receiving segments of the drop channel distributor. Corrector relay 11 is operated in the usual manner through the co-operation of line signals and signals from the correcting segments of the distributor, as is well known in the art. Nor- 110

mainly, operation of relay 11 causes a current flow from battery through a resistance, such as 13, and through the corrector magnets 14 to ground, thus producing a magnetic field in the vicinity of the tines of the vibrating tuning fork, thereby damping the vibrations of the fork. This increases the frequency of the vibrations of the tuning fork, thereby speeding up the drop channel distributor and synchronizing it with the transmitting distributor at the terminal station. In order that failure of the line section 4 connecting stations 1 and 2 be ineffective to cause a loss of synchronism between stations 2 and 3, the additional apparatus of the present invention is installed.

Two slow-release relays 8 and 9 are connected, one in each contact lead of the receiving relay 6. Normal operating signals will maintain both these relays in their operated or open positions, as shown in Fig. 2, thereby holding open the circuit to the biased slow-operating relay 10 which is common to both slow-releasing relays. The slow-operating relay 10 may be adjusted to require, say, five seconds current duration to operate. In the unoperated position of slow-operating relay 10, as shown in Fig. 2, the circuit from the contacts of corrector relay 11 to the corrector magnets 14 is normal, current being supplied to corrector magnets 14 through 1500-ohm coil 13 when corrector relay 11 is operated, 1500-ohm coil 12 being on open circuit.

When the line section 4 fails, line 16 of Fig. 2 likewise fails and the tongue of receiving relay 15 will lie against either one of its contacts 6 and the corresponding slow-releasing relay 8 or 9 will release its armature and close the circuit to the slow-operating relay 10. When this circuit has been closed for the predetermined time, the slow-operating relay 10 will close a circuit to the corrector magnets 14 through 3000 ohms resistances, 12 and 13 in series, thereby causing corrector magnets 14 to be less strongly energized, and cause the drop channel distributor to rotate at the approximate mean rate of speed.

This condition will be maintained until signals are again received over line section 4 and likewise line 16, which will operate receiving relay 15 and, subsequently, the corresponding slow-releasing relay 8 or 9, thereby restoring the biased slow-operating relay 10 to its normal position so that the corrector circuit will again function normally.

Although the invention has been shown as applied to a particular type of telegraph system, it is, of course, obvious to those versed in the art that it is equally applicable to other types of systems, and may be used in any circuit where synchronism is to be maintained in a corrected station or stations upon the failure of the master correcting station or pace setting station associated with the corrected station or stations.

The particular embodiment of the invention here described contemplates the use of the five-unit Baudot code, the employment of automatic transmission by perforated tape, and the use of rotary distributors of the cam type. This invention, however, may be used to advantage in connection with any other type of code, equal-letter or unequal-letter, and with means of transmission other than by tape, and is also suitable for use in connection with rotary distributors of the brush and segment type.

The modifications of systems other than that disclosed by Connery above will readily present themselves to those versed in the art.

While I have described but one embodiment of my invention and that with particular reference to a drop channel repeater, it is thoroughly understood that my device is not limited to such use, but may be used in numerous electrical systems requiring synchronism between received signals and those locally generated for further use.

What is claimed is:

1. In a signaling system, a plurality of stations, line sections connecting said stations, means at a first of said stations for synchronizing apparatus at the remaining stations therewith, and electromagnetic means at one of the remaining stations, said means being responsive to a failure of the line section from said first station for automatically causing apparatus at the balance of said remaining stations to be driven in synchronism with apparatus at said above-mentioned one of the remaining stations.

2. In a signaling system, a plurality of stations, line sections for successively connecting said stations, means at a first of said stations for synchronizing apparatus at the remaining stations therewith, and relays at one of the remaining stations, said relays being responsive to an open condition on the line section from said first station for causing apparatus at the balance of said remaining stations to be driven in synchronism with apparatus at one of the remaining stations.

3. In a signaling system, a plurality of stations, line sections connecting said stations, means at a first of said stations for synchronizing apparatus at the remaining stations therewith, and means comprising relay means at one of the remaining stations responsive to an open condition on the line section from said first station existing for a predetermined time interval for causing apparatus at the balance of said remaining stations to be driven in synchronism therewith.

4. In a signaling system, a plurality of stations, line sections connecting said stations, means at a first of said stations for synchronizing apparatus at the remaining stations therewith, and means comprising slow-release and slow-operate relays at one of the remaining stations responsive to a predetermined condition upon the line section from said first station existing for a predetermined time interval for causing apparatus at the balance of said remaining stations to be driven in synchronism with apparatus at the above-enumerated one of said remaining stations.

5. In a signaling system, a plurality of stations, line sections connecting said stations, means at a first of said stations for synchronizing apparatus at the remaining stations therewith and means at one of the remaining stations responsive to the failure of the line section from said first station to transmit signals for a predetermined time interval for causing apparatus at the balance of said remaining stations to be driven in synchronism with apparatus at the above-mentioned one of the remaining stations.

6. In a signaling system, a plurality of stations, line sections connecting said stations, means at a first of said stations for synchronizing apparatus of the remaining stations therewith, a plurality of additional stations connected with one of said remaining stations, said last mentioned station being a drop channel station connecting said first station with said additional stations for synchronizing apparatus

- thereat with the means at said first station, and a series of electromagnetic means responsive to the failure of said drop channel station to receive signals from said first-mentioned station 5 throughout a predetermined time interval for causing apparatus at the drop channel station to maintain apparatus at the additional stations in synchronism with the apparatus at said drop channel station.
- 10 7. In a signaling system, a plurality of stations, line sections connecting said stations, means at a first of said stations for synchronizing apparatus of the remaining stations therewith, a plurality of additional stations connected with one of said remaining stations, said last mentioned station being a drop channel station connecting said first stations with said means at said first station, and relays responsive to the failure of said drop channel station to receive impulses from said first-mentioned station throughout a predetermined time interval for causing apparatus at the drop channel station to maintain apparatus at both the additional stations and the balance of said plurality 25 of stations in synchronism with apparatus at said drop channel station.
8. In a signaling system, a plurality of stations, receiving and sending distributors at each of said stations, line sections connecting said stations, means at the first of said stations for synchronizing the distributors at the remaining stations therewith, and relays at one of the remaining stations responsive to a predetermined condition of the line section from said first station to transfer the synchronization of the distributors at the balance of said remaining stations to the above-enumerated one of the remaining stations.
9. In a signaling system, a transmitting station, a receiving station, an intermediate drop channel station having a receiving relay provided with marking and spacing contacts and adapted to receive signals from said transmitting station, line sections connecting said stations, means at said transmitting station for synchronizing apparatus at the remaining stations therewith, and transfer means at said drop channel station, said means comprising a pair of slow release relays one of said pair being disposed in a circuit including said marking contact, the other of said pair being disposed in a circuit including said spacing contact, either of said relays being responsive to a failure of the line section from said transmitting station for 100 a predetermined time interval, to transfer the synchronization of the apparatus at the remaining stations to said drop channel station.
